FRED C. MYER, OF SACRAMENTO, CALIFORNIA

COIN SELECTOR

Application filed November 12, 1929. Serial No. 406,619.

This invention relates to coin selectors and more particularly to means for selecting coins of a predetermined value and discarding all others, which may be applied to coin controlled vending machines, change delivering machines, or any coin controlled apparatus.

The principal object of the invention is to provide means to regulate the size of the coin chute by the coin itself, as it is inserted, to prevent vibration of the coin from side to side as it moves through the chute.

A particular object is the arrangement of the chute for the reception of a coin and the means of throwing the coin against an impact anvil in the end of the chute, the rebound therefrom determining the value of the coin from a predetermined valuation.

Another object is the provision of means to feed coins into the selector and means to prevent the operation of the coin feeding means without a coin therein.

Other objects and advantages will appear as the description progresses.

In this specification and the accompanying drawings the invention is disclosed in the form considered to be the best, but I do not wish to be understood as confining it to this form, because it may be embodied in other forms. It is also understood that in and by the claims following the description it is desired to cover the invention in whatsoever form it may be embodied.

In the three sheets of drawings:

Figure 1 is a sectional side elevation showing some of the principal parts of the coin selector and a portion of the housing.

Figure 2 is a front elevation of the same showing a portion of the housing and the relation of the coin feeder and operating lever thereto.

Figure 3 is a section looking from the rear of the housing.

Figure 4 is a sectional view showing a side view of the coin control chute mechanism.

Figure 5 is a sectional plan view of the coin controlled chute mechanism taken on the line 5—5 of Figure 4.

Figure 6 is a longitudinal sectional detail view of a portion of the coin operated slide.

Figure 7 is a plan view of the parts shown in Figure 6 in connection with a coin and stationary block.

Coin selectors are installed in connection with coin controlled mechanism in a housing containing the mechanism.

In this instance the coin control means is not shown, but a portion of the housing is indicated by the numeral 1. A coin feeder 2 is pivoted on the pin 3 in the brackets 4—4 riveted to the inside wall of the housing.

The coin feeder is normally held projecting from the housing so that a coin may be inserted in a recess or pocket 5 through the slot 6.

A plate 7 having a coin slot 8 in alignment with the slot 6 is provided and this plate extends down the side as shown at 9 to form a retaining side wall for the coin.

The plate may be a part of the housing but in this instance it is a separate piece secured by the rivet 10 to the housing.

The coin feeder is held in the projecting position by the spring 12 which projects the stop 11 on the feeder against the housing 1. The coin is carried into the housing by the feeder as it swings in on its pivot, the coin being pushed in by a thin plate 13 between a slide 14 and a stationary block 15 moving the slide a distance equal to the thickness of the coin. The slide is held in the position to which it is moved by the coin against the spring action for the purpose to be described hereinafter. The sliding runner 16 on the coin feeder will slide over the spring tension block 17 which is mounted on the slide 14 as shown in Figures 6 and 7 in detail, in which 18 is the spring and 19 and 20 are guide pins. Thus a tension is put on the slide to hold it from moving until the coin feeder returns to the projecting position.

When the coin feeder, having a coin therein, is pushed in until the portion 21 comes in contact with the block 22 on the vertical coin chute 23, the coin acts to push up a bolt 24 against the spring 25. A bell crank lever 26 pivoted at 27 on a bracket 28 and secured to the housing has one arm 29 pivoted to the bolt at 30 and the other arm 31 pivoted to a latch 32 supported in the bracket 33 and en-

gaging the vertical latch 34 as shown at 34' to hold it in the raised position against a spring 35 in the bracket 36, and when the latch 32 is drawn back the latch 34 drops down and rides on the top portion of the feeder until the notch 37 comes in alignment therewith. When the latch 34 drops therein and holds the coin feeder, the coin drops down the chute 23 into the horizontal chute 38 and comes to rest against the hammer 39 pivoted at 40 on the bracket 41.

A slide member 42 having bearings 43, 44 and 45 is provided with a latch 46 pivoted on the pin 47 in the slide. This latch engages the lower end of the hammer at the point 48 and is held engaged by the spring 49.

A spring 50 acts to hold the hammer against the resilient buffer 51. A hand lever 52 pivoted at 53 on the casing has a pin 54 below the pivot and which extends through the slot 55 in the side of the casing to the slide in which it is secured. The slide is retained in the forward position against the stop 56 by the spring 57.

23 A pin 58 in the slide is adapted to operate the bell crank lever 59 one way only. When the slide moves back, the pin 58 comes in contact with the latch 61, pivoted on the lever at 62 to swing freely over the pin. A spring 63 acts to hold the latch against the bell crank arm so that when the slide returns the pin strikes the latch on the reverse side and moves the bell crank lever to pull down on the rod 64, which is connected at its upper end to a lever 65 pivoted at 66 on the bracket 67. This lever is connected to the latch 34 so that the down pull on the rod 64 acts to raise the latch to the position shown in Figure 1.

The coin chute frame 38 comprises side walls 68 and 69, bottom 70 and end wall 71. The end wall has the impact anvil 72, the face of which is set on an angle predetermined to cause a predetermined genuine coin striking thereon to be thrown into a chute 73 leading to the coin control mechanism.

45 The coin chute 74 is formed by the wall 68 and the movable side wall 75 which is mounted on the springs 76 and adjustably held on the bar 77 by the threaded bolts 78 and nuts 79. These springs are very delicate and may be finely adjusted.

The bar carrying the springs is mounted on the pins 80 and 81 which are slidable in the side 69 and have the springs 82 and 83 tending to force the bar toward the coin chute.

63 A bar 84 adapted to be reciprocated is connected to the sliding pins by the links 85 and 86 by means of the pins 87 on the bar and pins 88 on the slidable pins.

63 The links 89 have pins 90 slidable in slots 91 in the slidable pins. The links 89 bear against the side wall 69 so that when the bar 84 is moved in the direction of the arrow the links will straighten out, pushing the slidable pins 80 and 81 and as the pins carry the mov-

able side of the chute, the space for the coin will be made larger.

The bar 84 is connected and controlled by the movement of the coin controlled slide 14 by means of a system of levers in which the lever 85' pivoted at 86' on the casing is moved in the direction of the arrows by the slide 14 connected at 87' as it is forced out by the insertion of a coin. This action operates the bell crank lever 88' pivoted to the casing at 89', causing the connecting bar 90' to raise the horizontal arm of the bell crank lever 91' and moving the vertical arm thereof in the direction of the arrow and carrying the bar 84 in the same direction by means of the connecting link 92 pivoted on the bar at 93. The bell crank 91' is mounted on the bracket 92' riveted to the casing.

A vertical pivot 94 allows for the slight outward movement of the bar 84.

A bracket 14' fixed to the casing by means of rivets affords a support for the slide 14. A spring 15' acts to hold the slide 14 against the fixed block 15 through the lever 85'.

The vertical depending arm of the bell crank 91' has the threaded portion 95 and the adjusting nuts 96 and 97.

This coin selector operates as follows:

A coin is inserted in the slot 8, and drops to the position shown in Figure 1. When the feeder 2 is pushed in, the pusher 13 comes in contact with the coin and carries it in, causing the coin to push back the slide 14 a distance equal to the thickness of the coin. Now the portion 16 rides over tension block 17 and forces it down to put a tension on the slide 14 to hold it from movement after the coin is pushed through by the pusher 13 which is thinner than any coin used and does not come in contact with the slide 14.

When the coin feeder is pushed in to the stop 22, the coin will roll into the chute 23 and drop into the slightly enlarged space in the coin chute and come to rest as shown in dotted lines in Figure 1. As the coin is pushed by the slide 14 it comes in contact with the vertical slide 24 and raises it and pulls back the latch 32 by means of the bell crank lever to release the catch 34 which drops down and into the notch 37, holding the coin feeder from return movement.

Now the lever 52 is pulled forward manually, moving the slide 42 back until the catch 46 swings the lower end of the hammer 39 clear, when the spring will cause it to snap back and strike the coin sending it through the chute to strike the impact anvil 72 with enough force to cause it to rebound on some such a trajectory as shown in dotted lines in Figure 4 to enter the chute 73 which guides it to the coin control mechanism.

When the lever 52 is pushed back, the pin 58 projecting from the slide comes in contact with the arm 61 and operates the bell crank lever to pull down on the rod 64 to

raise the latch 34 out of the notch 37 allowing the spring 12 to force back the coin feeder to its original position. If this coin feeder is pushed in without a coin therein, the latch 24 will not be lifted so the latch 34 will not be released to engage the notch 37 and thus the feeder will drop back. All coins except a coin of predetermined value will fall short of the chute 73 or be thrown over the chute. Means may be provided to bring all the discarded coins into a common receptacle or other chutes may be provided to catch the discarded coins and guide them to different receptacles.

Having thus described this invention what is claimed and desired to secure by Letters Patent is:

1. A coin selector of the class described, comprising a coin chute having an adjustable side wall, means to feed a coin to said chute, means to propel said coin through the chute, and means to control said adjustable side wall by the insertion of the coin, to prevent vibrations of the coin as it travels through the chute.

2. A coin selector of the class described, comprising a coin chute, a coin feeder to said chute, means to propel a coin through said chute, a movable side wall in said chute, means controlled by the insertion of a coin to adjust said movable wall to the thickness of the coin.

3. A coin selector of the class described, comprising a casing, a hinged coin feeder on said casing, a coin recess in said feeder, means to swing said feeder into the casing with a coin in said recess, a slidable bar in the path of motion of said coin, and adapted to be pushed back by said coin, a coin chute having a movable side and means connecting said slidable bar with said movable side whereby the insertion of a coin controls the chute and adjusts the chute to the thickness of the coin, and an impact anvil in the end of the chute.

4. A coin selector of the class described, comprising a casing, a coin feeder hinged to said casing, and adapted to swing thereinto, a coin slot in said feeder, a coin pusher in said feeder, adapted to push the coin into the casing when said feeder is pressed in, a spring latch to hold said feeder in the pressed in position, means to prevent said latch from holding said feeder, means actuated by the coin as it is carried in the casing to release said latch to allow it to hold said feeder until various operations are completed and means to release the latch to allow the feeder to return to its original position.

5. A coin selector comprising a casing, an approximately horizontal coin chute in said casing, means to feed a coin to said chute, means to propel said coin through said chute, an impact anvil at the end of said chute, a movable side wall in said chute, and means whereby the insertion of a coin controls said

movable side wall to conform to the thickness of said coin.

6. A coin selector comprising a casing, having a hinged coin feeder, a recess in said feeder to receive a coin, means to push said feeder into said casing, means to retain said feeder in the casing until all the coin selecting operations are completed, a coin chute, means to propel the coin through the chute, an impact anvil to receive said coin, means to catch the coin on the rebound from said anvil, and means to release said coin feeder to allow it to return to its original position.

7. A coin selector of the class described, comprising a casing, a pivoted coin feeder in said casing, a latch to hold said feeder, means operated by the insertion of a coin to release said latch to allow it to engage said coin feeder, a coin chute having an adjustable side to receive the coin from said feeder, means operated by the insertion to control said adjustable side to the size of the coin inserted, means to hold said side in the adjusted position, means to propel the coin through said chute, an anvil at the end of said chute to receive the impact of said coin, means to catch a coin having a certain trajectory and means to release the coin feeder to allow it to return to its original position.

In testimony whereof I have hereunto set my hand this 31st day of October A. D. 1929.

FRED C. MYER.
